UNITED STATES PATENT OFFICE.

JAMES ROSENBLUM, OF AMITE, LOUISIANA.

ENGINE-CRANKING DEVICE.

Application filed March 6, 1923. Serial No. 623,186.

The invention relates to engine cranking devices, and has for its object to provide a device of this character comprising a bracket arching the engine drive shaft at the forward end of a motor vehicle in which bracket a counter shaft is rotatably mounted. The counter shaft is provided with a large gear which meshes with a small gear carried by the engine shaft and is also provided with a hand operated fly wheel and by means of which an engine may be cranked without danger of injury if the engine backfires. The hand operated fly wheel forms means for allowing momentum to the counter shaft in the driving of the large gear, thereby insuring a quick and rapid rotation of the engine drive shaft.

A further object is to provide a gear drive for starting an engine, thereby reducing the amount of power necessary for starting the engine and insuring a rapid positive rotation of the engine shaft.

With the above and other objects in view the invention resides in the combination and arrangement of parts as hereinafter set forth, shown in the drawing, described and claimed, it being understood that changes in the precise embodiment of the invention may be made within the scope of what is claimed without departing from the spirit of the invention.

In the drawing:—

Figure 1 is a front elevation of a portion of the forward end of an automobile showing the cranking device applied thereto.

Figure 2 is a sectional view taken on line 2—2 of Figure 1.

Referring to the drawing, the numeral 1 designates the radiator of a conventional form of automobile and 2 the spring receiving channel disposed beneath the radiator. Secured to the upper side of the channel 2 by means of U-bolts 3 are the arms 4 of an upwardly extending bracket 5. The arms 4 extend outwardly and upwardly and converge towards each other and terminate in an enlarged portion 6 having a horizontally disposed bearing 7 therein. Rotatably mounted in the bearing 7 is a horizontally disposed shaft 8 and secured to said shaft 8 is a large drive gear 9, which drive gear meshes with a small driven pinion 10. The pinion 10 is carried by the engine drive shaft 11. It will be seen

that when the shaft 8 is rotated, that the large drive gear 9 will impart a rapid rotation to the gear 10, which gear is considerably smaller than the drive gear 10, consequently the engine drive shaft 11 will be rapidly rotated for starting the engine. However, to facilitate the rapid rotation of the shaft 8 and without danger to the operator from back firing of the engine, the said shaft is provided with a hand operated fly wheel 12, which when rotated adds momentum or inertia to the drive gear 9. The operator grasps the rim of the wheel 12 and rotates the same and it will be seen that the wheel is smooth and consequently in case of backfire there is nothing to come into engagement with the operator's hands and cause injury.

From the above it will be seen that an engine cranking device is provided, which is simple in construction, the drive shaft is driven through gear connections thereby increasing the driving power and consequently insuring a rapid rotation of the engine shaft and one wherein it will be impossible for the operator to be injured on backfire of the engine. It will also be seen that the fly wheel when rapidly rotated will gain sufficient momentum to insure a rapid and positive rotation of the engine shaft 11 through the gear connections 9 and 10.

The invention having been set forth what is claimed as new and useful is:—

The combination with a vehicle engine starting shaft, said shaft being disposed above a support, a radiator above said support, of a starting mechanism for said shaft, said mechanism comprising a bracket carried by the support and arching the shaft, said bracket being disposed forwardly of the support and radiator, a horizontally disposed shaft rotatably mounted in a bearing in the upper end of the bracket, a gear carried by said shaft, said gear being disposed forwardly of the bracket, a hand operated fly wheel carried by the horizontal shaft, said fly wheel being disposed forwardly of the gear carried by the engine starting shaft.

In testimony whereof I have signed my name to this specification.

JAMES ROSENBLUM.
